Primary Examiner — Garth Rademaker*Assistant Examiner* — Melanie Pellegrini(74) *Attorney, Agent, or Firm* — Levisohn Berger LLP(57) **CLAIM**

The ornamental design for a jewelry mounting head, as shown and described.

DESCRIPTION

FIG. 1 is a front and right side perspective view of a jewelry mounting head showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and

FIG. 8 is an enlarged top perspective view thereof; and,

FIG. 9 is an enlarged front view thereof.

The broken lines shown in the drawings represent environment and form no part of the claimed design.
